Primary Examiner — Cathron C Brooks*Assistant Examiner* — Sharon S Oum(74) *Attorney, Agent, or Firm* — Bass, Berry & Sims PLC(57) **CLAIM**

The ornamental design for a mobile device holder, as shown and described.

DESCRIPTION

FIG. 1 is a front view of a mobile device holder showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front perspective view thereof;

FIG. 8 is a rear perspective view thereof;

FIG. 9 is another front perspective view thereof with a sliding holding tab in an extended position; and,

FIG. 10 is another rear perspective view thereof with the sliding holding tab in an extended position.

1 Claim, 10 Drawing Sheets(56)
